UNITED STATES PATENT OFFICE.

CHARLES A. BACKSTROM, OF MILWAUKEE, WISCONSIN, ASSIGNOR TO BACK-
STROM-SMITH STEAM TURBINE & MANUFACTURING COMPANY, A COR-
PORATION OF WISCONSIN.

TURBINE NOZZLE-VALVE.

No. 856,206.

Specification of Letters Patent.

Patented June 11, 1907.

Application filed October 3, 1904. Renewed April 22, 1907. Serial No. 369,573.

To all whom it may concern:

Be it known that I, CHARLES A. BACK-
STROM, a citizen of the United States, resid-
ing at Milwaukee, county of Milwaukee, and
5 State of Wisconsin, have invented new and
useful Improvements in Turbine Nozzle-
Valves, of which the following is a specifica-
tion.

My invention relates to improvements in
10 turbine nozzle valves.

The object of my invention is to provide a
form of valve which will offer a minimum re-
sistance to the valve actuating devices and
which will close perfectly and be held to its
15 seat by the pressure of the motive fluid.

In the following description, reference is had
to the accompanying drawings in which,—

Figure 1 is a transverse sectional view of a
20 turbine embodying my invention and show-
ing a nozzle partition partially broken away
to expose a portion of a running wheel. Fig.
2 is a detail view of the same in axial section.
Fig. 3 is a detail view showing a portion of
25 the controlling lever and band valve in sec-
tion drawn to a plane of the nozzles and band
valve. Fig. 4 is a detail plan view of the
outer end of the controlling lever and a por-
tion of the band valve.

Like parts are identified by the same refer-
30 ence characters throughout the several views.

1 is a turbine casing; 2, a running wheel
provided with vanes 3, and 4 is a nozzle par-
tition having a nozzle ring concentric with
35 the vanes and arranged for an inward flow of
the motive fluid to the vanes through suit-
able nozzles 5.

Controlling levers 6 are pivotally secured
to the nozzle partition at 7 and off-set at
40 their outer ends 8 over the nozzle ring, the
latter having an outer surface curved out-
wardly in an arc concentric with that in
which the portion 8 of the lever swings. The
nozzles 5 are formed in groups, one group be-
45 ing located in each of these outwardly curved
or bulging portions of the nozzle ring. A
band 9 of flexible material is secured at one
end 10 to the nozzle ring at one side of the
group of nozzles, and extends from that point
50 of connection through a slotted or forked
guide arm 11 connected with the controlling
lever. The other end of the band is prefer-
ably looped inwardly and also secured to the

nozzle ring at 12 near the opposite end of the
group of nozzles from that at which the end
10 is secured. The band passes angularly 55
through the guide arm 11 in such a manner
as to rest flat on the bulging portion of the
nozzle ring between the guide and the end 10
where it is secured to the ring, thus closing
the nozzles which it covers. An increasing 60
number of nozzles is therefore covered as the
lever swings away from the end 10 of the
band and uncovered as the lever swings to-
ward that end.

The levers are actuated by a rod 15 which 65
extends through a suitable stuffing box at 16
and has its interior end connected with one
of the levers by a link 17. The levers are
connected with each other by a link 18, two
levers being illustrated in Fig. 1. It will be 70
understood, however, that any desired num-
ber of levers and valves may be employed,
or, if desired, other means may be employed
for actuating the valves without departing
from the scope of my invention. 75

Having thus described my invention what
I claim as new and desire to secure by Let-
ters Patent is,—

1. In a turbine, the combination of a noz-
zle partition provided with apertures, each 80
arranged to constitute an independent noz-
zle adapted for a separate delivery of mo-
tive fluid to the movable member of the tur-
bine; flexible material adapted to cover and
close the nozzle apertures; and means for 85
progressively bending the flexible material
outwardly from the partition to successively
uncover said apertures.

2. In a turbine, the combination of a noz-
zle partition provided with nozzle apertures; 90
flexible material adapted to cover and close
said apertures; a movable device for bending
said flexible material toward and away from
the partition; and means for maintaining a
uniformly varying relation between said de- 95
vice and the nozzle apertures.

3. In a turbine, the combination of a noz-
zle partition provided with nozzle apertures;
flexible material adapted to cover and close
said apertures; a movable device for bending 100
said flexible material outwardly and away
from the nozzle partition to successively un-
cover said apertures; a swinging connection
pivotally secured to said device and to a

fixed point of support; and means for actuating said device; said nozzle apertures being grouped in an arc corresponding substantially with that described by the outer end 5 portion of the swing connection.

4. In a turbine, the combination of a nozzle partition provided with nozzle apertures arranged in groups; a strip of flexible material secured to the partition adjacent to the 10 nozzles of each group and extended over the nozzle apertures in a position to close the same; and means for progressively bending the strip away from the partition.

5. In a turbine, the combination of a nozzle partition provided with a group of nozzle apertures comprising a strip of flexible material extended across said apertures, with one 15 end secured to the partition, and the other end looped inwardly beyond the nozzles and secured to the partition in reversed position; and means for progressively adjusting the 20 intermediate portion of said strip to and from

the apertured portion of the partition to successively open or close said nozzle apertures.

6. In a turbine, the combination of a nozzle partition provided with an off set apertured portion constituting a nozzle ring; a strip of flexible material secured to the nozzle ring and extended over nozzle apertures therein; a lever pivotally connected with a suitable support and provided with a guide 25 loosely engaging said strip, the inner portion of said guide being arranged in close proximity to the nozzle ring extending therefrom outwardly; and means for swinging said 30 lever; the outer surface of said nozzle ring being curved in correspondence with the arc described by said guide.

In testimony whereof I affix my signature in the presence of two witnesses.

CHARLES A. BACKSTROM.
